Attorney

UNITED STATES PATENT OFFICE.

WILLIAM COOKE, OF SHELTON, WASHINGTON.

OIL-BURNER.

1,200,084.

Specification of Letters Patent. Patented Oct. 3, 1916.

Application filed January 31, 1916. Serial No. 75,319.

To all whom it may concern:

Be it known that I, WILLIAM COOKE, a citizen of the United States, residing at Shelton, in the county of Mason and State 5 of Washington, have invented certain new and useful Improvements in Oil-Burners, of which the following is a specification.

This invention relates to wickless oil burners of that class which generate gas 10 from oil and burn the gas.

My object is to provide a retort that can be relied upon to produce a steady flow of gas, to prevent backfiring; to provide means for retaining the retort in fixed relation to 15 the generator under the varying conditions of expansion by heat, and to provide a gas jet which may be readily cleaned from soot and other obstructions.

To this end my invention consists in the 20 construction and combination of parts forming an oil burner hereinafter more fully described and particularly stated in the claim, reference being had to the accompanying drawing in which:

25 Figure I, is a side elevation of an oil burner according to my invention. Fig. II is a front elevation of the alcohol delivery device. Fig. III is a central vertical section partly in side elevation of my oil burner. 30 Fig. IV is a longitudinal section of the jet. Fig. V shows a horizontal section, partly in plan view, at line X, Fig. III.

These oil burners are usually made in pairs mounted on a single base 7, to fit into 35 the fire box under two lids of a cooking stove. The heater comprises a chamber having a circular inner wall 8, a floor 9, an outer wall 10, of sheet metal having many perforations 11, for the blaze to issue 40 through; a cap 12, which rests upon the outer wall and has a baffle ring 13 depending from it within the chamber 8, 9. An intake tube 14 passes down through the floor 9, and has a flange 15 resting thereon.

45 The retort comprises a pipe 16 adapted at one end 17 to engage the oil supply pipe, thence rising to the level of the floor and passing in a circle around the outer wall 10 a little below the lower level of the 50 perforations 11, and supported on brackets 18 that are provided with caps 19 and screw bolts 20; thence dropping to about the level of its starting point 17, and provided with a jet 21, the delivery nozzle 22 of which 55 is located centrally under the intake tube 14, up into which the nozzle enters a little

to prevent side puffs of air from causing back fire. The delivery opening 23 in the nozzle being necessarily very minute, is liable to become clogged by soot and foreign 60 matter in the oil, and such matter gathers in quantity in the bore or chamber 24 rendering a stoppage of the opening 23 liable at any moment if cleaning of the jet is neglected. To facilitate this cleaning and 65 insure its being well done, I fit a conical plug 25, having a shoulder 26, into one end of the jet 21 and provide a cap 27, with an internal shoulder to engage the shoulder 26, and with a screw thread to screw upon 70 the jet. This enables the operator to make a tight joint even where kerosene oil is used, and yet permits the full size of the bore to be opened for cleaning. The nozzle 22 is a plug like 25 excepting the delivery opening 75 23, and has the same advantages. It also opens the nozzle to be cleaned from the larger inner end opening. The brackets 18, integral with or rigidly attached to the heating chamber, hold the circular portion 80 of the retort 16, always in its fixed relation to the perforations 11, at which the burning takes place, be the contraction and expansion what it may in practice. The base piece 7 is formed as a pan at 30 to receive alcohol 85 to be burned directly under the chamber 8, 9 to heat it and the surrounding retort in starting them to generate gas. To pour alcohol into the pan by usual means when there is fire in the stove is dangerous, therefore I provide a funnel 27 that may be hung by the loop hole 28 at a safe distance 90 from the stove; a very small conducting pipe 29 that may be bent or swung as required to reach the pan 30, and a stopcock 95 31. By this means the desired quantity of alcohol may be easily and safely conducted to the pan at any time whether there is fire about the stove or not. In operation, oil is admitted to the retort at 17 and 100 the delivery regulated by the usual stopcock in the supply pipe, not shown. Burning alcohol in the pan 30 starts the conversion of oil into gas by heating the chamber 8, 9 and retort; this gas is delivered 105 by the jet nozzle 22 into the intake tube 14, then up into the said chamber where it passes down under the baffle 13, then up over the inner wall 8 to the burner apertures 11 in the outer wall 10 where it is 110 to be lighted by a match. The circular portion of the retort 16, located near the flame,

converts the oil into gas that would burn, but its quality as a heat producer is greatly improved by superheating it in the chamber 8, 9 where it is retained by the baffle arrangement for that purpose and finally produces a flame of intense heat. Fairly good results are produced if the wall 8 be located farther from the wall 10, or even if it be entirely removed, but the intake tube 14, 10 extending high up into the chamber 8, 9 and the baffle 13 depending around that tube below the level of its top are essential to the best results of this invention.

I claim:

- 15 In an oil burner, a heating chamber having a floor with a rising inner wall and a central opening; an outer wall of perforated sheet material removably attached to the

floor around and near to the inner wall; an intake tube passing through the floor and 20 having a flange resting removably thereon; a cap resting on the outer wall and having a baffle ring depending freely around the intake tube, and a delivery oil pipe located as a retort around the heating chamber and 25 secured thereto on brackets integral therewith, thence descending beneath the said intake tube and having a nozzle projecting a little up into the open lower end thereof.

In testimony whereof I affix my signature 30 in presence of two witnesses.

WILLIAM COOKE.
